UNITED STATES PATENT OFFICE.

WILLIAM A. REGENTZ, OF SAN FRANCISCO, CALIFORNIA.

PORTABLE FOLDING BED.

1,333,823.

Specification of Letters Patent. Patented Mar. 16, 1920.

Application filed June 27, 1919. Serial No. 308,622.

To all whom it may concern:

Be it known that I, WILLIAM A. REGENTZ, a citizen of the United States, residing in the city and county of San Francisco and 5 State of California, have invented a certain new and useful Improvement in Portable Folding Beds, of which the following is a specification.

My invention relates to improvements in 10 folding portable beds for use with motor vehicles and the like wherein a container operates in conjunction with foldable supporting means to contain and support a folding spring mattress.

15 The primary object of my invention is to provide an improved portable folding bed of a simple, cheap and effective construction which may be easily and readily folded and stored within a suitable box or container attached to the running board of a motor vehicle or the like, and as easily extended for use without necessarily removing the same from said running board.

20 It is also an object of the present invention to provide, in conjunction with the folding bed, a suitable and readily attachable shelter in the form of a tent, said shelter or tent being supported by the bed supporting structure in such a manner that the said tent may be used with the mattress detached to provide adequate shelter during the day time or when the tent is not being used for sleeping purposes.

25 A further object of the invention is to provide an improved folding support for a mattress that may be easily and readily folded into a comparatively small compass and stored within a container to which it is attached.

30 40 I accomplish these and other objects by means of the device disclosed in the drawings forming a part of the present specification wherein like characters of reference are used to designate similar parts throughout the said specification and drawings, and in which:

35 Figure 1 is a broken side elevation of my improved device partly in section to disclose the manner in which the mattress and supports therefor are connected to the container;

45 Fig. 2 is a partly broken plan view of Fig. 1 with the tent removed;

50 Fig. 3 is a side elevation, partly in section, of the device partially folded;

55 Fig. 4 is a broken plan view of Fig. 3;

Fig. 5 is a view similar to Fig. 3 but showing a further folded position of the supporting structure;

Fig. 6 is a broken plan view of Fig. 5 disclosing further progress in the folding process;

Fig. 7 is an elevation, partly in section, disclosing a still further advance in the folding process;

Fig. 8 is a broken plan view of Fig. 7;

Fig. 9 is a sectional view disclosing the device fully folded within the container; and

Fig. 10 is a broken plan view of Fig. 9 with the top cover removed.

Referring to the drawings the numeral 1 is used to designate a box or container having the front side 2 hingedly connected to the bottom 3 and the top or lid 4 hingedly connected to the top edge of the front side 2.

The bottom 3 of the box or container 1 is provided at the ends thereof with longitudinal extensions 6 by means of which said container may be secured to the running board 7 of a motor vehicle or the like, not shown.

Pins 8 are hingedly connected, as at 9, to the ends of the front edge of the bottom 3 of the box 1. Pivots connected to the pins 8 are folding longitudinal mattress supports comprising members 11 and 12 having slots 14 and 16 respectively. The members 11 are pivotally connected to the pins 8 while the members 12 are pivotally connected to the opposite ends of the members 11. Struts 17 are pivotally and slidably connected to the members 11 and 12 by means of suitable thumb nuts or screws 18 as disclosed in Fig. 1 of the drawings.

95 Each member 12 has pivotally mounted on one end thereof a shoe 19 to rest upon the ground and serve as a support for the members 11 and 12.

A foot piece 21 arranged parallel to and spaced apart from the box 1 has its ends pivotally connected to the ends of the members 12, said pivotal points being equal in distance apart to the distance between the pins 8, the purpose of which will hereinafter be more fully set forth.

100 Struts or braces 22 are pivotally connected adjacent the ends of the foot piece 21 and are adapted for engagement with the members 12 by means of thumb nuts or 110 screws 23 to rigidly connect and thereby prevent movement of the foot piece 21 re-

latively to the members 12. Uprights 24 are pivotally connected to the ends of the members 12 and rigidly held in such position by means of suitable struts 26 pivotally mounted 5 upon the said uprights 24 and connected to the members 12 by means of suitable thumb nuts 27.

Similar uprights 28 are pivotally connected to the back piece of the box 1 and 10 are likewise provided with struts 29 pivotally mounted on the ends of the box 1 and suitably connected to said uprights 28. Tent supports 31 are extended between the upper 15 ends of the uprights 24 and 28 to support a suitable tent 32 having suitable flapped opening to permit of entrance and egress to said tent 32.

As described thus far the structure provides a shelter or tent which may be occupied 20 during the time when not used for sleeping as in inclement weather or for dressing purposes.

For sleeping purposes a suitable spring mattress 33 is provided with a plurality of 25 springs 34 at each end, the springs 34 at the head of the mattress 33 being attached to a bar 36 secured within the box 1 while the springs 34 at the foot of the bed are attached to a bar 37 provided with hooks arranged 30 to engage the foot piece 21.

In operation the members 11 and 12 are arranged at angles to each other so that their point of connection rests substantially on the ground with the pivotally mounted shoe 35 19 serving to prevent penetration of said joint into soft or yielding ground.

The strut 17 serves to rigidly retain said members 11 and 12 in position while said members, thus rigidly held, serve to support 40 the foot piece 21 parallel to and apart from the box 1.

When folding the device into the container or box 1 the hooks 38 are first disengaged from the foot piece 21 and the mattress 33 is then laid back over the box 1. The tent 32 and supports 31 are then removed from the uprights 24 and 28 and said uprights released from rigid engagement with their respective members 12 and the 45 box 1 by releasing the struts 26 and 29 respectively, the struts 26 being moved to register with the uprights 24, as disclosed by the dotted arcs in Fig. 1 of the drawings, while the struts 29 are moved into the box 1 to the positions disclosed in full lines in Figs. 5 and 8 of the drawings.

The uprights 24 are next registered with the sides of the members 12 while the struts 28 are lowered to occupy longitudinal positions 60 within the box 1.

The struts 22 are next released and registered with the foot piece 22 as disclosed by the dotted arcs in Fig. 1 of the drawings.

The thumb nuts 18 of the member 17 are 65 next released and the members 11 and 12 are

folded together as disclosed in Fig. 5 of the drawings which movement will bring into coincidence the pivotal connections between the foot piece 21 and the pins 8 as disclosed in Fig. 6 of the drawings. Both sets of 70 folded members 11 and 12 may now be folded toward the box 1 upon the registering pivotal points and the pins 8, one of said pins being somewhat longer than the other to allow one set of folded members 11 and 75 12 to move above the other set, the natural resiliency of the connecting foot piece 21 readily allowing such movement.

The entire folded structure is then folded upon the hinges 9 to bring said structure 80 into the box or container 1 as disclosed in Fig. 9 of the drawings. The mattress 33 is next folded into the box above the folded structure just described and the tent supports 31 are placed upon the mattress with 85 pins 41, extending from the ends of the supports 31 seated within slots 42 in the ends of the box 1 provided for that purpose.

The front 2 and cover 4 of the box 1 is then closed to inclose the entire structure 90 minus the tent 32 which may be folded and stored away separately.

To set up the device above operation is reversed.

To further strengthen the device when 95 set up auxiliary struts 43 are pivotally connected to the insides of the ends of the box 1 and have their opposite ends attachable to the members 11 adjacent said box as disclosed in Figs. 1 and 2 of the drawings.

The device may be detached from the running board 7 of a motor vehicle and set up *per se*, by utilizing the front piece 2 and lid or cover 4 as legs or supports for the head of the bed as disclosed in Fig. 1 of the drawings. 105

It is evident that the mattress 33 may be temporarily detached from its supporting structure and the remaining tent portion used as a shelter.

Having thus described my invention, what I claim as new and desire to secure by Letters Patent is:

1. A portable folding bed, comprising a box having the front side hingedly mounted thereon; a cover hingedly mounted to the top edge of said front side; a pair of folding longitudinal supports hingedly and pivotally connected to the bottom of the inside of the box; a foot piece pivotally connected between the ends of the folding longitudinal supports; and a suitable mattress detachably connected to the foot piece and to the inside of the bottom of the box, said longitudinal supports and foot piece being foldable, with the mattress into the box. 115

2. A portable folding bed comprising a box adapted for mounting upon the running board of a motor vehicle or the like; a foot piece arranged longitudinally parallel with 120

not vertically as in Fig. 1 of the drawings.

the box and spaced apart therefrom; folding longitudinal supports hingedly and pivotally connected to the inside of the box at one end and pivotally connected to the ends of 5 the foot piece at the other ends thereof, each of said supports comprising two members pivotally connected and arranged at angles to each other and adapted for resting on the ground adjacent their pivotal connection; 10 means for rigidly retaining the two members in their proper relative positions; and a suitable spring mattress connected between the foot piece and the bottom of the inside of the box and foldable thereinto with the 15 longitudinal supports and the foot piece.

3. A portable folding bed comprising a box adapted for mounting upon the running board of a motor vehicle or the like and having the front and top hingedly connected 20 whereby said top and front may be positioned to support said box above the ground; a foot piece arranged longitudinally parallel with the box and spaced apart therefrom; a pair of pivot pins hingedly mounted upon 25 the bottom of the inside of the box and adjacent the ends thereof, one of said pins being longer than the other; a folding longitudinal support pivotally mounted upon

each pin at one end and having their opposite ends pivotally connected to the ends of 30 the foot piece, said supports being arranged to rest on the ground to form a support at approximately their central portions; means for rigidly retaining the supports in a supporting position; and a suitable spring mattress 35 detachably connected between the foot piece and the box, said mattress being foldable with the longitudinal supports and foot piece into said box.

4. A portable folding bed comprising a 40 box having the top thereof hinged to the front side and said front side hinged to the front of the bottom of said box, whereby said box may be opened, said top and front side being adapted to form a support for the box; 45 a folding frame, comprising a foot piece and substantially parallel with folding longitudinal supports, hingedly connected to the front of the bottom of the box and foldable thereinto; and a suitable spring mattress de- 50 tachably connected between the bottom of the box and the foot piece of the frame.

In witness whereof I hereunto set my signature.

WILLIAM A. REGENTZ.
